UNITED STATES PATENT OFFICE.

JOHN ALEXANDER LOW WADDELL AND IRA GRANT HEDRICK, OF KANSAS CITY, MISSOURI.

IRON RAILWAY-BRIDGE.

SPECIFICATION forming part of Letters Patent No. 737,679, dated September 1, 1903.

Application filed November 5, 1902. Serial No. 130,151. (No model.)

To all whom it may concern:

Be it known that we, JOHN ALEXANDER LOW WADDELL, civil engineer, residing at 2708 Forest avenue, and IRA GRANT HEDRICK, 5 civil engineer, residing at 2216 East Eighth street, Kansas City, in the State of Missouri, both citizens of the United States, doing business as consulting engineers at the new Nelson Block, in said city, have invented an Improvement in Iron Railway-Bridges, of which the following is a specification.

In those cases where new railroads are built requiring only a single track at first, but destined ultimately to be provided with a double 15 track, a large part of the expense of making the change from single to double track is involved in substituting double-track for single-track bridges. On the other hand, if double-track bridges are built in the first instance 20 the additional expense thereof as compared with single-track structures will breed a large loss in the form of interest charges during the years elapsing between their first building and the time when double track is finally 25 laid.

It is the object of this invention to provide two forms of bridge so related that one will serve as a single-track bridge, but may be converted into the second form for carrying 30 a double track at very little greater final outlay than if the double-track bridge had been originally built. At the same time the single-track form costs but little more than an ordinary single-track structure, and thus nearly 35 the entire extra interest charge, otherwise lost, will be saved. Moreover, the change from single to double track takes far less time than is involved in other and prior methods.

40 Our invention is illustrated in the accompanying drawings, wherein—

Figure 1 is a transverse vertical section of both forms of bridge. Fig. 2 is in part a top view and in part a horizontal section of Fig. 45 1 with tracks and ties removed. Figs. 3, 4, and 5 are details of joints and fastenings on a larger scale.

In Fig. 1 the first or single-track form of bridge is shown in full lines, forming a part 50 of the entire or second form of bridge, the additional parts of which are shown in dot-

ted lines. In the first or single-track form of bridge the vertical trusses are shown at 1 and the horizontal cross-trusses at 2. The lateral diagonal bracing is shown at 3 and 55 the floor-beams at 4. When the second form of bridge is completed, the two tracks will be carried on the usual ties supported by four stringers, of which 5 and 6 in Fig. 1 form a part of the first form of bridge, and 7 and 8 60 (shown in dotted lines) are subsequently added. While the first form of bridge is being used, the ties 9 and rails 10 are supported by the stringers 5 and 6, which are placed, as shown, to leave room for swinging in the 65 stringers 7 and 8 when the second form of bridge is to be constructed.

The first form of bridge, or that shown in full lines in Fig. 1, differs in the following particulars from the form it would be given if 70 intended only to serve as a single-track structure: In the first place the horizontal distance between trusses must be sufficient in the clear to give room for accommodating two tracks of proper gage and at the proper distance apart. 75 The floor-beams 4 must be made sufficiently strong, as indicated in the drawings, to support a double track and the live loads incident to double-track practice. The entire lateral system is made strong enough for a two-track 80 bridge. The trusses must be made strong enough to carry the live load incident to single-track practice and the weight of the original bridge; but the connecting details for the floor-beams must be strong enough for the 85 double-track structure. These connecting details are shown in Fig. 3, where the end of a floor-beam is indicated at 4 and the plates and rivets for connecting the same with the truss 1 are clearly shown. At 11 in this figure 90 is shown in dotted lines the details of attachment of one of the second set of stringers. In converting this first form of bridge into a second form the stringers 7 and 8 are added, and the tracks are then laid over the stringers 95 6 and 8 on one side and 5 and 7 on the other. A second set of vertical trusses 12 is erected just outside of and parallel to the trusses 1 on both sides. Each of the second set of trusses is preferably connected to the corresponding inner truss by diaphragms 14 at proper intervals above the beams. At the

top and bottom the trusses 1 and 12 are further connected by stay-plates 15, and shorter stay-plates 16 are employed for connecting successive horizontal chords 17. The details 5 of these diaphragms and stay-plates are shown in Figs. 3, 4, and 5, wherein Fig. 3 shows the attachment opposite the floor-beams in elevation, Fig. 4 shows an elevation of the connecting means opposite the junctions of the 10 lateral braces with the trusses, and Fig. 5 shows a plan of details of attachment at the top of a pair of trusses 1 and 12.

It is obvious that in building our first form of bridge the piers and abutments should be 15 made from the first large and strong enough to accommodate our second form of bridge.

What we claim is—

1. A preparatory single-track bridge having clear space enough between trusses to accommodate four stringers properly located for 20 a two-track structure, said bridge having two longitudinal stringers so placed as to serve ultimately as the two inner stringers for the four-track road, and having a single track

supported by said stringers, substantially as 25 described.

2. In a preparatory single-track bridge, trusses far enough apart for a double track and calculated to safely carry only the live load of a single track and the dead weight of 30 the preparatory single-track bridge, floor-beams calculated to safely carry the double-track structure and connecting details between the trusses and floor-beams, also calculated to safely carry the double-track structure, substantially as described. 35

3. In a railway-bridge, pairs of trusses on each side, vertical diaphragms riveted to both trusses in each pair, and horizontal stay-plates at the ends of the pairs of trusses, substantially as described. 40

In witness whereof we have hereunto set our hands in presence of two witnesses.

JOHN ALEXANDER LOW WADDELL. [L. S.]
IRA GRANT HEDRICK. [L. S.]
